UNITED STATES PATENT OFFICE

127,841

DESIGN FOR A PHOTOGRAPHIC ENLARGING APPARATUS

Albert Drucker, Chicago, Ill., assignor to Burke & James, Inc., Chicago, Ill., a corporation of Illinois

Application January 21, 1941, Serial No. 98,226

Term of patent 14 years

To all whom it may concern:

Be it known that I, Albert Drucker, a citizen of the United States, residing at Chicago, in the county of Cook and State of Illinois, have invented a new, original, and ornamental Design for a Photographic Enlarging Apparatus, of which the following is a specification, reference being had to the accompanying drawing forming a part thereof.

The figure is a perspective view of a photographic enlarging apparatus, showing my new design. The numerals appearing at the upper end of the adjusting arm at the point where the same is attached to the enlarging head are merely representative.

I claim:

The ornamental design for a photographic enlarging apparatus, as shown and described.

ALBERT DRUCKER.
